CLAIM

The ornamental design for a sanitary countertop machine
for storing and dispensing particulate ice and for
dispensing beverage, substantially as shown and de-
scribed.

DESCRIPTION

FIG. 1 is a perspective view looking downward at the
front, left side and top of a sanitary countertop machine
for storing and dispensing particulate ice and for dispensing
beverage, showing my new design;

FIG. 2 is a front elevational view thereof;

FIG. 3 is a side elevational view of the right side
thereof;

FIG. 4 is a side elevational view of the left side thereof;

FIG. 5 is a rear elevational view thereof; and

FIG. 6 is a top plan view thereof;

The bottom is substantially planar and unornamented.
